Specification for Design.

Patented Aug. 24, 1920.

Application filed February 16, 1920. Serial No. 359,003. Term of patent 7 years.

To all whom it may concern:

Be it known that I, FREDERICK E. GREENE, a citizen of the United States, residing at Mount Vernon, Westchester county, State of New York, have invented a new, original, and ornamental Design for a Handle for an Automobile-Door Lock or Similar Article of Manufacture, of which the following is a specification, reference being had to the accompanying drawing, forming a part thereof.

In said drawing:

Figure 1 is a side view of a handle embodying my design.

Fig. 2 is an edge view of the same.

I claim—

The ornamental design for a handle for an automobile door lock or similar article of manufacture substantially as shown.

FREDERICK E. GREENE.
